UNITED STATES PATENT OFFICE.

MARTIN FRANZ MAYER, OF SEATTLE, WASHINGTON.

LIFEBOAT.

Application filed December 10, 1923. Serial No. 679,855.

To all whom it may concern:

Be it known that I, MARTIN FRANZ MAYER, a citizen of the United States of America, residing at Seattle, in the county of King 5 and State of Washington, have invented certain new and useful Improvements in Life-boats, of which the following is a specification.

This invention relates to improvements 10 in life boats involving the use of a single keelson and the disposition of the floor frames of such height and in such relation to the keelson as to provide compartments for storing water and food containers, or the 15 loose equipment of the life boat.

The invention further provides the sides of the boat of such construction as to provide for the convenient housing of air tanks or other buoyant material containers.

20 The invention also provides the use of thwarts, which are removably secured in a manner to insure against the spreading of the sides of the boat and to include a substantial stanchion support for the thwarts as required 25 in boats of this type.

The invention is illustrated in the accompanying drawings, in which:

Fig. 1 is a broken view in vertical longitudinal section of the improved boat.

30 Fig. 2 is a transverse section thereof illustrating particularly the mounting for the thwarts.

Fig. 3 is a sectional view showing the means designed in connection with the improved life boat to permit nesting of the boats.

The improved life boat which aside from the details hereinafter referred to, may be 40 constructed in any usual or preferred manner, includes a keelson 1, extending longitudinally and centrally of the boat to the respective ends thereof, with which keelson is connected the appropriate member of transversely arranged floor timbers 2, to which 45 latter may be secured the bottom 3 and floor 4 of the boat. The floor timbers extend transversely relative to the keelson and are of sufficient height or depth to provide a series 50 of spaces 5, between the keelson, floor timbers, bottom, and floor of the boat, to receive containers as 6 for the storage of food, water and the like, which spaces are also adapted to receive any appropriate loose equipment 55 for the life boat.

55 The sides of the boat have the usual rib timbers 7 secured to the floor timbers by me-

tallic knees 8, on the outer side of which ribs are arranged the usual side walls 9, and on the inner side in spaced relation the usual battens 10, the latter being in spaced relation as 60 indicated. The ribs are of sufficient dimension transverse the boat to provide in the side walls between the ribs a series of compartments or spaces 11, in which may be placed air containers, indicated at 12, or containers with cork or other buoyant material, whereby to provide for maintaining the buoyancy of the boat when in use. 65

Secured on the appropriate batten on each side of the boat are thwarts 13, these latter being removably held in connection with the particular battens by dowel pins 14, which may be conveniently forced into position or removed therefrom at will. The thwarts are further secured in position by substantial 70 rods 15, having a hinge or swivel connection with the underside of the thwarts adjacent the respective ends thereof, with the free or lower ends of the rods formed as hooks 16, to engage in eyes 17 secured to the side of the 75 boat. As the thwarts are more or less permanently secured in place by the dowel pins, it is apparent that the sides of the boat will not spread, and hence the rods 15 may be of such length as to tightly engage the eyes 17, 80 whereby the rods act in effect as stanchion supports for the thwarts, as is required in 85 this type of boat.

In order to provide a sufficient number of 90 life boats to accominodate the maximum 90 number of passengers of a vessel without requiring excess space for the storage of such life boats, it is necessary that the life boats should be nested, and to secure this result a 95 supporting thwart 18 is provided in the boat below and preferably between the main thwarts, the supporting thwart being removably secured in position by dowel pins 19 engaging blocks 20 secured between or to the appropriate battens. These supporting 100 thwarts are in such position as to permit one life boat to be nested and supported in another in a manner to permit their convenient separation when required for use. Obviously in the nesting of the life boats, 105 the main thwarts will be removed, being conveniently replaced when the life boats are to be used, as will be evident.

Claims:

1. A life boat having the main thwarts 110 secured to the walls of the boat by removable dowel pins, rods extending from said thwarts

to the sides of the boat and removably connected to such sides, the connection of the rods between the thwarts and boat providing a substantially rigid structure to serve as 5 stanchion supports for the thwarts, and a supporting thwart removably secured to the sides of the boat below the main thwarts and arranged at such height above the bottom of the boat as to receive and support the bot- 10 tom of a nesting boat.

2. A life boat having main thwarts removably secured to the walls of the boat, and a supporting thwart removably secured to the sides of the boat below the main thwarts, said supporting thwarts being arranged at 15 such height above the bottom of the boat as to receive and support the bottom of a nesting boat.

In testimony whereof I affix my signature.
MARTIN FRANZ MAYER.
